UNITED STATES PATENT OFFICE.

HORATIO B. RUGGLES, OF MEDFORD, MASSACHUSETTS, ASSIGNOR TO BOSTON AUTOMATIC BED COMPANY, OF BOSTON, MASSACHUSETTS, A CORPORATION OF MAINE.

DESIGN FOR A BRACKET.

SPECIFICATION forming part of Design No. 36,770, dated February 2, 1904.

Application filed June 18, 1903. Serial No. 162,144. Term of patent 3½ years.

To all whom it may concern:

Be it known that I, HORATIO B. RUGGLES, a citizen of the United States, residing at 15 Emerson street, in the city of Medford, in the county of Middlesex and State of Massachusetts, have invented a new, original, and ornamental Design for Brackets, reference being had to the accompanying drawings, in which—

Figure 1 is a front elevation of bracket; and

Fig. 2 is a side elevation of said bracket, showing my new design.

What I claim is—

The ornamental design for a bracket, as shown.

HORATIO B. RUGGLES.
